CLAIM

The ornamental design for a glove, as shown and described.

DESCRIPTION

FIG. 1 is a bottom, right, and rear perspective view of an ornamental design for a glove, depicting how the glove would appear when being worn;

FIG. 2 is a bottom plan view of the glove of FIG. 1;

FIG. 3 is a top plan view of the glove of FIG. 1;

FIG. 4 is a right side elevational view of the glove of FIG. 1;

FIG. 5 is a left side elevational view of the glove of FIG. 1;
FIG. 6 is a front elevational view of the glove of FIG. 1;
FIG. 7 is a rear elevational view of the glove of FIG. 1;
FIG. 8 is a top, right, and front perspective view of the glove of FIG. 1;

FIG. 9 is a bottom, right, and rear perspective view of the glove of FIG. 1, depicting how the glove would appear when unworn;

FIG. 10 is a bottom plan view of the glove of FIG. 9;

FIG. 11 is a top plan view of the glove of FIG. 9;

FIG. 12 is a right side elevational view of the glove of FIG. 9;

FIG. 13 is a left side elevational view of the glove of FIG. 9;

FIG. 14 is a front elevational view of the glove of FIG. 9;
FIG. 15 is a rear elevational view of the glove of FIG. 9;
FIG. 16 is a top, right, and front perspective view of the glove of FIG. 9;

FIG. 17 is a section view along line 17-17 of FIG. 3;

FIG. 18 is a section view along line 18-18 of FIG. 3;

FIG. 19 is a section view along line 19-19 of FIG. 11; and,
FIG. 20 is a section view along line 20-20 of FIG. 11.

The longer dash broken lines are included for the purpose of illustrating portions of the glove that form no part of the claimed design. The shorter dash broken lines are included for the purpose of illustrating stitching that forms no part of the claimed design. The circular portions shown in the top, left, and front views of the glove are shown in broken lines and form no part of the claimed design. The section views are provided for the sole purpose of clarifying the shape of

(Continued)

the claimed design and, as such, any materials and internal structure depicted in the section views form no part of the claimed design.
